UNITED STATES PATENT OFFICE.

WILLIAM LE ROY BRYANT, OF SPRINGFIELD, VERMONT.

GRINDING MACHINE.

Application filed July 20, 1921. Serial No. 486,080.

To all whom it may concern:

Be it known that I, WILLIAM LE Roy BRYANT, a citizen of the United States, residing at Springfield, in the county of 55 Windsor and State of Vermont, have invented new and useful Improvements in Grinding Machines, of which the following is a specification.

This invention has relation to grinding

10 machines of the type in which the work is suitably held in work supports and is rotated during the grinding operation.

One of the primary objects of the invention is to provide certain improvements for 15 increasing the production and enhancing the accuracy of operation of such machines, and also to enable the machine to grind different diameters of the work at one operation, thereby saving a rehandling of the work as

20 would be necessary if one portion of the work having a certain diameter were ground in one machine and another portion of the work having a different diameter were ground in a second machine or by a second 25 operation.

The further objects of the invention are to secure a greater stability of the work by eliminating any marked over-hang of the work supports or centers; to provide im- 30 proved means for mounting the grinding wheel and the work-supporting mechanism so that one is fixedly held and the other is moved about an axis to effect the relative feed of the work and the wheel; to provide

35 for an improved automatic control of the feeding mechanism; to provide an automatic control for the work holders by which the work may be automatically engaged and disengaged or released; and to provide an 40 automatic control for the water which is delivered to the grinding wheels so that the flow of water may be stopped automatically at the completion of the grinding operation; and to provide an automatic control 45 for the work-rotating mechanism so that a cessation of rotation of the work may be effected on the completion of the grinding operation. Additional objects of the invention are to provide an improved truing 50 mechanism for the grinding wheel in which a better and more stable control is effected;

to provide for a relative reciprocation and transverse feed of the truing mechanism of the grinding wheel, in which one of the instrumentalities is mounted to move towards the other about a fixed center; to provide template or control bars which are interchangeable and adjustable so that the accurate truing of the wheels is not dependent upon the skill of the operator; and to 60 provide for accurate truing of grinding wheels of different shapes, including those wheels which have portions which vary in diameter. The invention has further for its object to provide numerous other improvements in construction and mode of operation, all of which are illustrated on the drawings, are described in the following specification, and referred to in the appended 65 claims.

The machine, which I have illustrated as constituting an embodiment of my invention, may be provided with grinding wheels of different kinds or shapes, so that it may be used in the grinding of a bar having a 70 predetermined diameter or it may be utilized in grinding bars having portions of different diameters, all at one operation, so that the machine is capable of a great variety of uses in finishing work having quite 75 widely varying characteristics. It is semi-automatic in character; that is, it requires that the operator shall insert the work manually in position to be engaged by the work supports. After the machine is set in operation by the operator, however, the grinding operation is automatically performed and the machine is brought to a state of rest when the operation is completed. While the feed is automatic, yet the operator may manually advance the work rapidly into grinding position without interfering with the operation of the automatic feed. The parts are preferably so arranged 80 and operated that, when the work has been fed to a predetermined extent, the operation of the feeding mechanism is reversed and the work and the wheel are separated and the feeding mechanism brought to a state 85 of rest with the work and the wheel in relatively retracted positions. With the cessation of the operation of the feeding mecha-

70

- nism, the rotation of the work is stopped automatically and the work is released by the work-holding devices, and at the same time the water is shut off automatically.
- 5 When a fresh piece of work has been placed in position by the operator, the operator then may, by suitable controlling devices, start the machine in operation so that the work is gripped by the work-holding devices, the work is rotated, the feeding mechanism is started in operation, and the water is turned on. In the particular embodiment of the invention selected for illustration, the work holders are supported upon a swinging member movable about a fixed axis and adapted to be reciprocated longitudinally of such axis if the character of the work requires such reciprocation. The work holders may be bodily adjusted manually simultaneously longitudinally of said axis, or they may be reciprocated manually longitudinally of said axis, but in addition I provide mechanism for automatically reciprocating the work holders longitudinally of the work during the grinding operation, and I have illustrated an improved mechanism by which this may be accomplished.
- 20 I have thus briefly referred to only a few of the salient features or characteristics of the machine which is illustrated on the drawing, the other features being described in detail in the following specification.

On the drawings,—

Figure 1 represents in front elevation a grinding machine embodying the invention.

Figure 2 represents an elevation of one end of the machine.

Figure 3 represents an elevation of the other end of the machine.

Figure 4 represents, on a larger scale and in front elevation, the combined oil tank and control box on the front of the machine.

Figure 5 represents a vertical transverse section on the line 5—5 of Figure 1.

Figures 6 and 6^A together represent a longitudinal section on the line 6—6 of Figure 5, all on a larger scale.

Figure 7 represents a longitudinal section through the grinding wheel and its supporting and grinding mechanism on the line 7—7 of Figure 5.

Figure 8 shows in section one end of a work-supporting member and illustrates the mechanism for rotating the work, in which the spindle and center pin are rotatable.

Figure 9 represents a longitudinal section through the oil tank and control box, and shows the mechanism for effecting the automatic feed for the work.

Figure 10 illustrates the mechanism for effecting the longitudinal reciprocation of the work.

Figure 11 (Sheet 1) illustrates the connections by which the water is automati-

cally controlled, and shows the parts in the position which they assume when the water is shut off.

Figure 12 (Sheet 2) shows a portion of the work-feeding mechanism, the figure representing a section on the line 12—12 of Figure 1.

Figure 13 (Sheet 2) represents a section on the line 13—13 of Figure 12 and shows the adjustable member for engaging a stop and checking the feed of the work.

Figure 14 (Sheet 3) represents a section through the grinding wheel on a vertical plane transverse to the machine, and illustrates the truing mechanism in operating position.

Figure 15 (Sheet 10) represents a partial development of the work-feeding worm wheel.

Figure 16 (Sheet 11) represents in longitudinal section a portion of a grinding wheel having a single cylindrical face of the same diameter from end to end.

Figure 17 (Sheet 11) shows in detail a portion of the mechanism for controlling the supply of water, and represents a section on the line 17—17 of Figure 1.

Figure 18 (Sheet 11) represents a relief valve which is utilized as a part of the mechanism for controlling the rotation of the work.

Figures 19 to 22 inclusive (Sheet 9) illustrate different forms of work and the respective grinding wheels which may be utilized in finishing the same, each figure representing a portion of a grinding wheel and the work to be ground thereby.

Figure 23 (Sheet 12) illustrates a template or control bar for the truing mechanism, and the mechanism by which said control bar is adjustably and removably supported.

Figure 24 illustrates in perspective and on an enlarged scale a portion of the bar shown in Figure 23.

Figures 25, 26 and 27 represent, on an enlarged scale, sections on the lines 25—25, 26—26, and 27—27 of Figure 23.

Figure 28 illustrates more or less conventionally certain of those portions of the machine which are operated by hydraulic pressure and the various pipe connections.

Figures 29 and 30 illustrate mechanically-operated mechanism for controlling the automatic feed of the work.

Figure 31 represents the same in longitudinal vertical section.

Figure 32 represents a section on the line 32—32 of Figure 31.

Figure 33 illustrates the operation of the weight which forms a part of the operating mechanism.

Before proceeding to describe the machine illustrated on the drawings thus briefly re-

ferred to, I desire to have it understood that the invention is not limited to the particular embodiment thereby illustrated, that many different changes may be made in the machine without departing from the spirit and scope of the invention as defined in the claims, that the phraseology herein employed is for the purpose of description and not of limitation, and that the drawings are 10 more or less conventional.

Proceeding to a description of the illustrated machine,—50 illustrates a hollow bed having suitable front, rear and end walls. On the upper face or table formed by the 15 bed there are two upright end standards 51, 52, which at their upper ends support two parallel bars 53, 54, one of which supports a truing mechanism and the other of which supports the work-holding and rotating 20 mechanism.

The work carrier, on which the work supports are mounted, comprises end arms 55, 56 and a longitudinal bar or table 57 connecting the lower ends of said arms and having a cylindrically concave supporting face 58, as best shown in Figures 5, 6 and 6^A. Preferably the arms 55, 56 are cast in hollow form for the sake of lightness, and they are clamped to the bar 54. The upper portions 25 of the arms may be split and provided with clamping screws 59. As a result of this construction, the work carrier, by loosening the clamp screws 59, may be adjusted longitudinally of the bar 54 and then 30 clamped rigidly thereto, so that, by moving the bar axially, the work carrier may be moved therewith. By mechanism, which I shall subsequently explain, the bar may be moved manually or automatically in an axial 35 direction for the purpose of effecting either an adjustment or a reciprocation of the work in lines parallel to the axis of the work. As shown in Figures 6 and 6^A, the uprights 51, 52 may be provided with tapered bushings 60, 61, in which the bar 54 is journaled and in which it may be moved longitudinally. These tapered bushings may be adjusted to compensate for wear by nuts 62, 63, 40 abutting against the inner faces of the uprights. By mechanism, subsequently to be explained, the work carrier and its supporting bar 54 may be swung about the axis of the bar 54 for the purpose of advancing the work to and withdrawing it from the grinding 45 wheel.

The grinding wheel and its operating mechanism.

The grinding wheel, which may be rotated 60 continuously irrespective of the other operations of the machine, is secured upon a grinding wheel shaft indicated at 65 (see Figures 5 and 7). This shaft is journaled in a carriage indicated as a whole at 66 which 65 is capable of adjustment horizontally and

transversely of the axis of the shaft 65. To this end the carriage is gibbed on a guideway 67 which is rigidly secured on the bed 50. An abutment screw 68, journaled in a bracket secured to the front end of the guide 70 member 67, extends into a threaded aperture in the front end of the carriage 66 so that, by rotating the screw, the carriage may be adjusted back and forth on the guideway so as to advance or retract the grinding wheel 75 towards or from the work. This adjustment is desirable to adapt the machine for work of greatly varying diameters and also to compensate for reduction in diameter in the grinding wheel due to wear. After the 80 grinding wheel carriage has been adjusted to position, it may be clamped in place rigidly by tapered gibs 69, 70. The gibs 70 operate between a dependent flange 71 on the carriage and a guideway 72 to hold the grinding wheel carriage against motion longitudinally of the axis of the grinding wheel shaft, whereas the tapered gibs 69 are located beneath the guide rail 73 and between it and a bar 74 bolted to the carriage, so as to confine the carriage against vertical movement. Inasmuch as the guide rail 72 has a beveled undercut complementary to a flange 75 on the carriage, the adjustment of the tapered gibs 70 also binds the carriage against vertical 95 movement. Thus the carriage may be held with great rigidity in any position to which it may be adjusted. The grinding wheel shaft 65 is journaled in bushings 76, 77, set in uprights 78, 79, formed on the carriage 100 66. Between the uprights 78, 79, the carriage is formed with a well or receptacle 80 for the reception of a suitable lubricating material, this well being closed by a cover 81 having a removable cap 82 through which 105 lubricant may be introduced into the well. At one end the grinding wheel shaft 65 is provided with a flange 83 and a reduced portion 84 to which the hub of the grinding wheel may be removably bolted or otherwise secured. Preferably the machine is 110 provided with a plurality of interchangeable grinding wheels for operating upon work of different kinds. Each wheel may with convenience comprise a hub 85 having an internal projecting flange 86 which may be bolted or otherwise secured to the flange 83 of the shaft 65. The flange 86 encircles the reduced end 84 of the shaft, and between them is placed a hardened steel bushing 87. 115 The hub of the grinding wheel may with convenience be made of aluminum or other suitable material. The grinding wheel proper, or that portion which is employed for grinding the work, is annular and is 120 clamped between an undercut flange 88 projecting radially from the hub and a removable clamping member 89, which is likewise undercut and which is secured to the face of the hub by screws 90. In the form shown in 130

Figure 7, I provide three grinding or abrading members 91, 92, 93, all of which are of different diameters and which may be of different kinds of grinding material if desired. Between these members are provided additional spacing and clamping members 94, 95. The flange 88, the clamp 89, and the spacers 94, 95 form dove-tail annular grooves into which complementary portions of the 10 abrading or grinding members are clamped. In Figure 16, I have shown the hub 85 as provided with a single abrading or grinding member 96 which is provided with a cylindrical exterior of the same diameter from end to end. It will be observed that in this case the member is of such axial length that it projects to some extent beyond the end of the hub, and consequently I employ a clamp 97 having an elongated hub portion 98 to accommodate the abrading or grinding member. Instead of a single cylindrical abrading member 96, a plurality of disks 96' of equal diameter may be employed as indicated in Figure 19. These grinding members may take different forms according to the character of the operation to be accomplished. In Figures 19, 20 and 21, I have shown portions of different grinding members which may be utilized. In addition to those shown in Figures 19 and 20 I have shown one member 99, in Figure 21, which is double tapered, and another member 100, in Figure 22, the face of which is concave. From these Figures 19 to 22 inclusive, it will be seen that, by these respective grinding or abrading members, the work may be finished or ground in different forms.

Referring once more to Figure 7, it will be observed that the grinding wheel, considered as a whole, is enclosed within a water guard 101 which rests upon a straight flange 102 formed on the upright 78 of the carriage 66 (see Figure 3). This guard is provided with a lug or ear 103 which may be clamped adjustably to the carriage 66 (see Figure 5). For this purpose, the carriage may be provided with an undercut groove 104 into which the head of a clamping bolt 105 may be inserted, and on the end 50 of which a nut 106 is screwed. As a matter of construction, anti-friction balls 107 may be located between the guard 101 and the flange 102 to support the weight of the guard and make it easy to adjust the guard. 55 The guard is provided with a face cover 108. The front portion of the guard is open, as shown in Figure 5, so that the work may be brought into engagement with the grinding wheel, and the lower portion of the guard is 60 flared downwardly somewhat as at 109 so as to deliver the water which is carried thereto by the grinding wheel. Any suitable means may be utilized for driving the grinding wheel at the desired speed. In Figure 3, I have illustrated at 110 an electric motor,

the frame of which is bolted to the rear wall of the bed 50. The rotor shaft 111 of the motor is provided with a pulley 112 from which power is transmitted to the various operative portions of the grinding machine, including the grinding wheel shaft. The belt 113, which is driven by the pulley 112, tracks about a pulley 114 which is axially aligned with the grinding wheel shaft 65 and which transmits power thereto. The pulley 114 might be mounted directly on the end of the grinding wheel shaft 65, but I regard it as highly desirable that this shaft should be relieved of any torsional strains to which it would be subjected if the pulley were secured directly thereto. Consequently the pulley is keyed to a shaft 115 which is in approximate axial alignment with the shaft 65 but which is mounted in a bearing frame 70 rigidly secured to the upright 79 of the carriage 66. This bearing frame is indicated at 116 and it is secured by screws 117 to a boss formed on the upright 79 of the carriage 66. The shaft 115 is journaled in ball bearings 118, 119, with which the bearing frame is 80 supplied and which hold it against axial movement. Between the two shafts 115 and 65, I employ a universal drive which comprises a cross pin 120 passed through a transverse aperture in the end of the shaft 65 and which is capable of rocking about its axis 85 therein. To the shaft 115, there is secured a head 121 having shouldered sockets into which the ends of the pin 120 project. The ends of the pins may be flattened to provide 90 faces to engage the end walls of the sockets. The flat faces 122, 123 on the pin 120 are preferably at a slight angle to each other, and the complementary faces of the sockets in the head 121 overlap them a relatively 95 short distance to cause the pin 120 to be slightly rotated about its axis so that both faces are under equal pressure and thus transmit a balanced drive to the shaft 65. By providing this balanced or universal 100 drive, it is not absolutely essential that the axes of the shafts 115 and 65 should be in exact alignment, as power will be transmitted to the grinding wheel shaft under all normal 105 operating conditions, even though the alignment is not perfect. Consequently, since the belt strain is removed from the grinding wheel shaft 65, the life of the bushings in which it is journaled will be greatly prolonged and there will be no tendency to bend 110 or distort the shaft. The belt 113, which transmits power to the grinding wheel shaft, passes under a pulley 124 on what I may term the main drive shaft 125, and also under a belt-tightening pulley 126, as shown 115 in Figure 3. This last-mentioned pulley 126 is journaled in a swinging frame 127 on a stud shaft 128 so that the pulley 126 is held 120 downwardly by the force of gravity to take up any slack in the belt. To this swinging 125

frame there is connected an arm or lever 129 (see Figure 3) which may be lifted to release the belt whenever occasion therefor may demand.

5 *The work carrier.*

By inspection of Figure 5, it will be observed that the work carrier depends normally from the bar 54 in front of the grinding wheel. The movement of the work, which is carried by the work carrier, is in a curvilinear path towards or from the grinding wheel, whereas the grinding wheel and its carrier are adjusted in rectilinear paths towards or from the work carrier. As has been explained, the adjustment of the grinding wheel carriage is ordinarily effected only when the machine is being set up for work of a relatively large or a relatively small diameter, or when the grinding wheel of one size is substituted for a grinding wheel of another size, or where a grinding wheel has been reduced in diameter to a considerable extent by use. The work carrier, however, is swung about its axis to effect a feeding movement of the work towards the grinding wheel or its withdrawal from grinding position.

I will now explain the means by which the work is held during the grinding operation and is rotated about its own axis. I have already explained that the work carrier is provided with a face or supporting surface 58 which is transversely concave. The curvature of this face, as shown in Figure 5, is such that the face is concentric with the axis of the work centers for a purpose to be explained. Referring now to Figures 6 and 6^A, it will be observed that the two end arms 55, 56 of the work carrier are provided with centers 130, 131, the former being the tail center and the latter the head center. The tail center is adjustable towards and from the head center to accommodate work of different lengths. In the arm 55 there is formed a tubular bearing 132 to receive a quill 133 in which there is mounted a slideable plunger 134. This plunger at its inner end is socketed to receive the tapered body of the center 130. The entire quill is bodily movable longitudinally to locate the center 130 in proper position to engage the end of a bar of work, the other end of which is engaged with the center 131, whereas the plunger 134 may be moved to cause the engagement of the center with and its disengagement from the end of the work. By a mechanism subsequently to be explained, the plunger is automatically operated by power under the control of the operator. Inasmuch as the quill may be bodily advanced to the left from the extreme position shown in Figure 6 and the center thus caused to project or overhang beyond the bearing 132, I provide means

for supporting the center on the curved table or supporting face of the work carrier. To accomplish this result, the quill 133 is provided with a segmental flange 135, the periphery of which engages the curved face 58 of the work carrier, as best shown in Figure 5. The quill should be held against rotation, and hence I bolt on the bar or longitudinal member 57 of the work carrier a guide bar 136 which enters a groove 137 formed in the segment 135. This guide bar 136 has an undercut groove into which the head of a bolt 138 is inserted, said bolt emerging into a cavity 139 formed in the face of the segment and being provided with a nut 140 so that the segment may be rigidly secured to the guide bar 136 after the quill has been adjusted to the desired position. It will be understood that the quill is adjusted only when setting up the machine for work of a particular length, whereas the plunger which carries the center is automatically actuated each time it is necessary to engage and release the work before and after the grinding operation. To protect the bearings against the access of grit, a guard 141 is secured to the end of the quill as shown in Figure 6.

The head center 131 is inserted in a spindle 142. In one form of the particular embodiment of the invention which I have illustrated, this spindle is held against rotation and the work is rotated by a driving head, but I may, if desired, provide the spindle with a chuck as shown in Letters 95 Patent No. 1,290,896, granted to me on January 14, 1919, or as hereinafter described. As illustrated in Figure 6^A, the spindle is held against rotation by a screw 143, being mounted in bearings afforded by the end 105 arm 57 of the work carrier. In this case, the driving head 144 is provided with a hub 145 which is journaled on the spindle 142 and which is provided with a driving pin 146 such as ordinarily employed. The driving head 144 is provided with a flange 147 having internal spiral gear teeth for engagement with a spirally toothed pinion 148 secured to a shaft 149. This shaft is journaled in suitable bushings 150, 151, located 115 in suitable apertures formed in the arm 56, and it is provided with a pulley 152 by which rotation may be imparted thereto to effect the rotation of the driving head. A belt 153, which engages the pulley 152, is 120 driven by a pulley 154 (see Figures 1 and 2), mounted on a shaft 155 secured in a swinging frame 156. Compounded with the pulley 154 is a cone pulley 157 driven by a belt 158 from a cone pulley 159 on the 125 main drive shaft 125. The swinging frame 156 is pivoted at 160 and normally lies horizontally so that the pulley 154, by force of gravity, keeps the belt 153 taut, and, as a result, power is transmitted from the drive 130

shaft 125 to the driving head of the work-rotating mechanism. By swinging the frame 156 upwardly, the belt 153 will be loosened so that the transmission of power 5 will be terminated. An arm 161 is connected to the swinging frame 156 and projects forwardly to the front of the machine, where it is in a position to be grasped by the operator. Mechanism is provided by which 10 this arm is automatically raised at the completion of the grinding operation, but I will reserve the description of this portion of the machine to a later part of this specification. I may here state that, when the 15 arm 161 is raised automatically, I provide for cutting off the flow of water to the grinding wheel.

From the description thus far given of the work carrier and its adjuncts, it will be 20 seen that the work carrier is provided with work supports which in the present instance consist of centers or center pins and their supporting members, and also with devices for effecting the rotation of the work. It 25 will be also apparent that these various instrumentalities are all so arranged that bars of different lengths may be properly held and presented to the grinding wheel.

30 *Reciprocating mechanism for the work carrier.*

The work carrier may be reciprocated longitudinally of the work axis, and thus longitudinally of the bar 54 whose axis is 35 parallel to that of the work axis, so as to effect an axial movement of the work while it is in engagement with the grinding wheel. In some cases, however, it is not desirable to have this longitudinal movement of the 40 work carrier, in which event the mechanism for effecting the reciprocation of the work support is rendered inactive. The entire work carrier may be adjusted longitudinally of the work axis so as to locate any pre-determined part of the work in proper relation to the grinding wheel. To this end, the bar 54, as shown in Figure 6, is provided with rack teeth 162 which extend partway around its periphery. With the 45 rack thus formed, there is engaged a pinion 163 secured on a shaft 164 journaled in a block 165 into which the end of the bar 54 projects. The end of the shaft 164 is angular in cross section, as shown at 166 in 50 Figure 10, so that, by applying a wrench or handle thereto, the pinion 163 may be rotated in one direction or the other to move the bar 54 longitudinally of its axis, the block in the meantime being held against 55 movement. I also provide means by which the block itself may be rocked or reciprocated back and forth to effect the automatic longitudinal reciprocation of the work carrier. To accomplish this result, an arm or lever 167 is pivoted on a pintle 168 mounted

in lugs 169 projecting from the upright 52 of the frame. This lever or arm 167 is provided with an upwardly projecting yoke 170 which embraces a pin 171 inserted in the block 165 and located almost directly above the pintle 168. Consequently, by rocking the lever 167 about the axis of the pivot or pintle 168, the block 165 and the bar 54 may be reciprocated. The lever 167 is automatically oscillated about its axis by any suitable mechanism driven from the main power shaft. For example, as shown in Figure 10, the main drive shaft 125 is provided with a worm 172 which intermeshes with and drives a worm wheel 173 mounted loosely on a shaft 174 which is horizontally arranged transversely above the shaft 125. The bed 50 is provided with an end extension or housing 175 through which the shaft 125 extends, the walls of this housing being apertured to receive bushings 176, 177, into which the shaft 174 is journaled. The axis of the shaft 174 is parallel with the axis of the pintle 168 on which the lever 167 is pivoted and hung. On its rear end, the shaft 174 is provided with an eccentric pin 178 which projects into an aperture in a plate 179 arranged to slide in a guideway 180 formed in the rear face of the lower end of the arm or lever 167 (see Figures 1 and 10). Consequently, when the shaft 174 is rotated, the lever 167 is oscillated about its axis. The worm wheel 173 is keyed to a clutch member 181 which is loosely mounted on the shaft 174. Splined to the said shaft there is a complementary clutch member 182 which may be moved to engage that at 181 by a yoke 183 secured to the end of a sliding pin 184. An arm 185 of a two-armed lever, pivoted at 186 and having its other arm 187 formed as a handle and projecting forwardly to the front of the machine so that it may be grasped by the operator, extends into the housing 175 and is bifurcated so as to engage a cross pin 188 passed through the yoke-carrying pin 184. By depressing the handle 187, the clutch member 182 may be engaged with its complementary clutch member 181 so that power will be transmitted from the main drive shaft 125 to the eccentric-carrying shaft 174. As the shaft 174 rotates, the eccentric 178, in oscillating the lever or arm 167, also moves the slide 179 up and down in its guideway 180. I utilize this movement of the plate 179 in determining the relative position of the parts when the clutch is to be disengaged to stop the rotation of the shaft 174. It will be observed that the pin 184 projects through the rear end of the housing (the left end in Figure 10) and is beveled or frusto-conical so that it may be brought into alignment with and engage a socket 189 in the plate 179. A spring 190 is interposed between the end of the arm 185

and a washer 191 engaging a cross pin 192. If the operator desires to throw the clutch out of operation so as to stop the reciprocation of the work carrier, the end of the handle 187 is raised so as to compress the spring 190, the pin 184 in the meantime being held in its clutch-engaging position by the engagement of the end of the pin with the plane face of the plate 179. As soon, 5 however, as the plate 179 rises far enough for the end of the pin 184 to project into the socket 189, the pressure of the spring is sufficient to cause the pin to be moved to the left in Figure 10 so as to enter the socket 10 189 and thus carry the clutch member 182 out of engagement with the clutch 181. The eccentric 178 is so located on the end of the shaft 174 that its major axis is in the horizontal plane of the axis of the shaft, as 15 shown in Figure 1, when the pin 184 enters the socket 189 and the rotation of the shaft ceases. In this position, the lever 167 is locked, with the bar 54 carried to its fur- 20 thermost position to the right in Figure 1. 25 The object of this is to effect the cessation of reciprocation of the work carrier at the right hand end of its movement, particularly when shouldered work is being ground, as the larger grinding wheels are to the 30 right of one facing the machine. This is desirable furthermore, because, as will be subsequently explained, the work carrier carries the control template or bar which governs the action of the truing mechanism 35 on the wheel, and it is also desirable that the work carrier should be stopped always at the same point in truing the wheel for any particular grinding operation. From the foregoing description, it will be seen 40 that the work carrier may be reciprocated by hand by rotating the shaft 164 and its pinion 163 in opposite directions while the lever 167 is locked against movement, or may be reciprocated automatically by the 45 power-transmitting mechanism driven from the main driving shaft. In the last-named event, the automatic reciprocation of the work carrier is under the control of the operator who may throw the automatic mech- 50 anism out of operation at any time by manipulation of the handle 187. So long as this handle 187 is in the position shown in Figure 10, the work carrier will remain at rest so far as longitudinal reciprocation 55 is concerned, and under these circumstances, the work carrier may be fed towards and from the work, as is desirable in some cases, as for instance in grinding concave or tapered diameters. 60 *Mechanism for feeding the work carrier.* For effecting a relative transverse feed of the work and the grinding wheel, I employ a single-speed automatic feed mechanism by 65 which the work and the grinding wheel are brought into grinding relation and continued in that relation until the work has been reduced to the desired diameter, after which the work and the tool are separated, whereupon the feed is automatically discontinued. 70 Provision is made, however, by which the operator may manually effect a feeding or withdrawing movement of the movable element. Inasmuch as in the present embodiment of the invention the work is advanced 75 toward and withdrawn from the grinding wheel, the automatic feeding mechanism is employed to move the work carrier. The work carrier, as will be remembered, swings about an axis and the feeding mechanism is 80 arranged as illustrated in Figure 5, so that a sliding element mounted on the bed engages a bar or template on the work carrier. The longitudinal member 57 of the work carrier is provided with a dependent 85 portion 196, to which is bolted a guide bar or template 197 which extends longitudinally thereof, and against this bar, at right angles thereto, is placed a relatively stationary but slidable bar or member 198 90 which is supported by the bed. As best shown in Figure 12, the slide 198 is cylindrical and is also formed at its outer end with a screw thread so that it performs the function of a feed screw. This bar or slide 95 is splined to a bushing 200, placed in a box 201 bolted to the bed. The former or outer end of the feed screw extends into a nut 202 which is journaled in a bushing 203 in the front wall of the box. On the inner end of 100 the nut which projects into the box, there is keyed a gear 204 with which is engaged a pinion 205 fast on a shaft 206 which projects forwardly through the box and has keyed thereto a disk 207 provided with 105 handles 208. By virtue of this construction, it will be seen that, by manually rotating the shaft 206 and thereby effecting the rotation of the nut 202, the feed screw or slide 198 will be advanced to feed the work 110 carrier towards the grinding wheel, and, by rotating the disk 207 in the opposite direction, the carrier will be retracted. It will be observed in this connection that the arm 55 is provided with a right-angle horizontally-extending bar 209, on the extremity of which is placed a weight 210, as shown in Figure 5, so as to swing the work carrier to the right from the position shown in 115 Figure 5. This ensures a constant firm engagement between the guide bar 197 and the feed bar or screw rod 198. I provide means by which the advance of the work carrier towards the grinding wheel may be limited. For this purpose, the outer end of the nut 202 is formed or provided with a worm wheel 211. A worm carrier 212 is journaled on a nut 202 and is arranged to receive a worm 213 intermeshing with the worm wheel 211, as shown in Figure 13, the jour-

nal bearing for the worm being indicated at 214. The end portions of the worm are provided with collars 215 pinned thereto. By rotating the worm, it and the carrier may be caused to revolve about the axis of the worm wheel. The worm functions as an adjustable stop and either end may be brought into engagement with a stationary stop which takes the form of a rotatable pin 216 inserted in a socket in the front wall of the box 201. This pin is placed in the path of revolution of the worm so that it may be engaged by either end thereof and thus stop the rotation of the nut and the advancing or retracting movement of the feed bar 198. The pin or stop member 216 has a knurled head 217 by which it may be grasped for rotation and it is also recessed at 218 so that it may be rotated through an arc of 180° from the position shown in Figure 13 so as not to interfere with the free revolution of the worm and its carrier about the axis of the nut. For feeding the work carrier, the nut 202 is rotated in the direction of the arrow in Figure 13, and in this figure the nut is illustrated as having been rotated far enough to bring the end of the worm into engagement with the pin 216 and thus stop the feeding movement of the work carrier towards the grinding wheel. The limit of feeding movement of the work carrier may be varied by adjusting the worm and its carrier about the worm wheel 211, and this may be accomplished by manually rotating the worm 213, either collar 215 affording means to be grasped by the operator in rotating the worm.

The mechanism for automatically feeding and withdrawing the work carrier is operated from the main driving shaft 125. This shaft, as shown in Figure 3, is provided with a pulley 219, which by a belt 220 drives a pulley 221 on a shaft 222, see Figure 9. The shaft 222 is journaled in bearings 223 at the lower end of what I may term a "feed box" indicated as a whole at 224 and which is bolted to the front of the bed. The feed box is shown in front elevation in Figure 4. As will be subsequently explained, the feed box serves as a reservoir for water, oil, or other liquid utilized in the hydraulic system which controls the operation of various parts of the machine, including the feed mechanism. The shaft 222 is provided with a cone pulley 225, from which, by a belt 226, power is transmitted to a cone pulley 227 pinned to a shaft 228 located on the top of the feed box. This shaft is journaled in bushings 229, 230, placed in a cylindrical cavity 231 formed in the upper wall of the box, and it is capable not only of rotation but of longitudinal sliding movement to a limited extent. Between its ends, the shaft is provided with two worms 232, 233, of opposite pitch, either of which may be

brought into mesh with a worm wheel 234. The worm wheel 234 is formed as an annulus and it is mounted on a disk 207, as shown in Figure 12. For this purpose, the disk is formed with a shouldered bearing 235 on 70 which the worm is journaled and on which it is held by a plate 236, through which screws 237 are screwed into the disk or wheel 207. Between the heads of the screws and the plate 236 are placed springs 238 which exert sufficient pressure on the plate to frictionally clamp the worm 234 against the disk or wheel 207 to cause them to rotate together under working conditions. Consequently, when either the worm 232 or the worm 233 80 is intermeshed with the worm wheel 234, the shaft 206 and the feed bar 198 will be actuated to move the feed carriage in one direction or the other as the case may be. Even though one of these worms is engaged with the worm wheel and is causing the rotation thereof, the operator, by exerting sufficient pressure on the handles 208 of the disk or wheel 207, may speed up the rotation of the shaft 206 to hasten the feeding 90 or withdrawing movement of the work carrier. Thus, when the machine is started in operation and the feed mechanism is working, the operator may rotate the wheel 207 rapidly to advance the work carrier to a 95 point where the work is in engagement with the grinding wheel, after which the continued rotation of the shaft 206 will be effected through the power-transmitting connections between the shaft 228 and the main 100 drive shaft 125. The longitudinal movement of the shaft 228 to bring either of the worms 232 or 233 into engagement with the worm wheel 234 may be effected by mechanical means or by fluid pressure as may be desired, and I have illustrated in the drawings both forms of means by which this may be accomplished. In the embodiment of the machine, illustrated in Figures 1 to 28 inclusive, I employ fluid-operated mechanism 110 for effecting the control of the feeding movement. In this case, as shown in Figure 9, the shaft 228 is formed with a piston or plunger and the bore of the cylindrical cavity 231 serves as a cylinder in which the piston is adapted to reciprocate, so that, when the fluid is admitted to one side or the other of the piston 239, the shaft 228 will be moved in one direction or the other. The worms 232, 233 are spaced far enough apart 115 so that the shaft may occupy a neutral position, as shown in Figure 9, with both worms disengaged from the worm wheel 234, and this is the position which the shaft assumes when the machine is out of operation, as, for example, when it is desired to remove a piece of work from the centers or insert a new piece therein.

I shall now describe the means by which the admission of fluid to the cylinder is con- 130

trolled. I have stated that the feed box serves as a reservoir for the fluid. In Figure 9, it will be observed that the feed box is hollow so as to provide a large reservoir or chamber 240 which may contain a body of oil, water or other liquid as indicated at 241. From this reservoir, the liquid is pumped and distributed by conduits or pipes for effecting the desired operation of the several instrumentalities. On the end of the feed box there is secured a pump of any suitable character. For example, it may consist of a casing 242 provided with pump gears 243, the inlet to the pump casing being indicated at 244. The pump shaft 245 is driven from the shaft 222 by a pulley 246, a belt 247, and a pulley 248. From the delivery end of the pump, a conduit, which is indicated conventionally in Figure 28 as a pipe 249, extends to a valve chest 250 formed in the top of the feed box. Within this valve chest there is a sliding tubular valve 251 which controls two outlet ports 252, 253, communicating respectively with ducts 254, 255, which terminate in ports 256, 257, leading into opposite ends of the cylinder 231 on both sides of the piston 239. The valve 251 is provided with a recess 258 of sufficient length so that, when the valve is in its intermediate or neutral position as shown in Figures 9 and 28, communication will be cut off between the conduit 249 and the conduits 252, 253. By moving the valve in one direction or the other, the liquid may be delivered to either of the two conduits. Leading from the valve chest there are two outlet ports 259, 260 diametrically opposite the ports for the conduits 252, 253, and the valve is provided with the annular grooves 261, 262, so that, when the valve is in position to admit fluid to one of the ports as at 253, the exhaust liquid from the conduit 254 may pass through the valve chest to the exhaust port 259, and, when the inlet port 252 is in communication with the conduit 259, the exhaust from the conduit 255 will pass through the valve chest to the exhaust port 260. These two exhaust ports 259, 260 communicate with a conduit 263 which leads back to the lower end of the reservoir 240 in the feed box. The valve may be shifted both automatically and manually. Preferably the shifting of the valve is accomplished in such manner as to cause the work carrier to be fed to the extreme limit of its movement towards the grinding wheel, and then to be withdrawn to its original starting position, and then come to a state of rest. When it is again desired to start the feeding operation, the valve must be shifted manually. The valve is provided with a pin 264 which extends through a slot 265 in the valve chest so that the valve may be moved in one direction or the other thereby. Within the pin 264, there is a smaller spring-pressed pin 266 whose beveled end may be caused to engage either of two notches 267, 268, on a sleeve 269 mounted on the reduced end of the shaft 228 for a purpose to be explained. Placed on the pin 264, there is a handle 270 which may be grasped by an operator. This handle is formed with a foot or plate 271 which rests on the top surface of the valve chest and is adapted to slide with the valve. A stop 272 is set in the top of the valve chest so as to limit the sliding movement of the handle 270 and therefore of the valve to the left so as to stop the valve in the neutral position shown in Figure 9, in which fluid is cut off from both sides of the piston 239 in the cylinder 231. When the parts are in this position, the valve handle 270 may be raised far enough to free it from the stop 272, whereupon the operator may move the valve to the left sufficiently to permit fluid to enter the cylinder 231 through the conduit 254 for the purpose of moving the shaft 228 bodily to the left to bring the feeding worm 233 into mesh with the worm wheel 234, whereupon the rotation of the shaft 228 will be imparted to the worm wheel 234 to cause the feeding movement of the work carrier. This movement of the work carrier will be continued until the stop (the worm 213) engages the pin 216, as shown in Figure 13. In other words, the small worm 213 will be moved from the position shown in Figure 9 to the position shown in Figure 13. As soon as the parts reach this last-mentioned position, namely in Figure 13, the feed of the work carrier is positively stopped, but, as the shaft 228 continues to rotate, while the worm wheel 234 is held against rotation, it is obvious that the shaft 234 will itself be fed or moved to the right in Figure 9. At this time, the spring-pressed pin 266 is engaged with the socket 267 in the sleeve 269, so that, as the shaft 228 moves to the right, it carries the valve 251 to the right with it far enough to close the port 252 and open the port 253, whereupon fluid is delivered to the left-hand end of the cylinder 231, so that, by fluid pressure, the right-hand movement of the shaft 228 is continued until the piston completes its stroke to the right, at which time the valve 251 is at the extreme right, sleeve 269 has moved so that pin 266 engages socket 268 and the reversing worm 232 is in mesh with the worm wheel 234. Thereupon the work carrier is fed or moved away from the work. The reverse rotation of the worm wheel 234 and the wheel 207 now brings the stop (the small worm 213) around in a direction opposite that indicated by the arrow in Figure 13 until its end engages the pin 216, as shown in Figure 9, whereupon the reverse feed of the work carrier ceases. As the

shaft 228 continues to rotate, however, by reason of the engagement of the worm 232 with the worm wheel 234, the shaft is caused to be fed to the left and this feeding movement continues until the foot of the handle 270 engages the stop 272. During the initial movement of the shaft 228 to the left, it carries the valve 251 with it, and, when the foot of the handle 270 engages the stop 272, the valve is in the neutral position as shown in Figure 9. This cuts off the supply of the liquid or fluid from both sides of the piston 239 and leaves the shaft 228 in a neutral position with both worms 232, 233 disengaged from the worm wheel 234. The reverse feeding movement of the work carrier therefore ceases as soon as the reverse rotation of the worm wheel 234 is stopped, and shortly thereafter, as soon as the shaft 228 has moved sufficiently to bring the valve into a neutral position, the entire feeding mechanism is thrown out of operation, although the worm shaft 228 continues to rotate, being driven continuously from the main drive shaft.

Automatic work engaging and rotating mechanism.

I have previously stated that, in the machine thus selected as an embodiment of the invention, mechanism is provided by which the work supports are caused automatically to engage and release the work, and also by which the rotation of the work is automatically started and stopped. The same pump, which is utilized to supply pressure for controlling the operation of the feed mechanism, may be utilized in controlling the operation of the work gripping and releasing mechanism. It will be recalled, referring to Figure 6, that the center or center pin 130 is mounted in a sleeve or plunger 134, and that in turn this member is mounted in a sleeve 133. The rear end of this last-mentioned sleeve is formed to constitute a cylinder 273 and the rear end of the sleeve 134 is enlarged to constitute a piston 274 located in the cylinder. The cylinder is provided with two ports 275, 276, with which communicate the two conduits 277, 278, respectively. These conduits may be of a semi-flexible character so as to permit of the bodily adjustment of the sleeve 133 as previously described. The conduit 278 communicates with that at 252 leading from the main valve chest, whereas the conduit 277 communicates with that at 253. When the fluid passing from the main valve enters the cylinder 273, through the conduit 278, the piston 274 and the sleeve 134 are moved to the left to cause the center to engage and grip the work. This takes place as soon as the valve is shifted manually to start the feeding mechanism in operation. It is necessary that the work

should not be engaged with too great pressure, and I therefore provide a pressure relief valve which is indicated in Figure 28 at 279. A branch conduit 280 leads from the conduit 278 to the relief valve, and a relief pipe 281 leads from said valve to the return conduit 263. Within the relief valve is placed a spring-pressed valve member 282 which normally closes the port leading to the conduit 280. This spring is kept at such tension, by adjustment of a screw plug 283, so long as the pressure of the center pin against the work is not excessive or more than is necessary. When this pressure is exceeded, however, the valve member 282 is raised so as to permit the liquid to pass out from the relief valve through the conduit 281. I also preferably employ a relief valve which is connected with the main supply conduit 249 leading from the delivery end of the pump. This valve is shown conventionally in Figure 28 at 284 and it contains a valve member 285 against which a spring 286 exerts pressure. A branch conduit 287 leads from the main supply pipe 249 to the relief valve casing, and the port is normally closed by the valve member 285. A relief pipe 288 leads from the valve casing back to the reservoir 240. Consequently, if at any time there is an excess of pressure, as when the piston 239 reaches one or the other extreme of its movement, liquid is permitted to circulate from the pump back through the relief valve to the tank or reservoir 240. The conduit 278 may be provided with a manually-operated three-way valve 2781, so that the center 130 may be restrained from dropping the work when the valve 251 is operated, as in setting up the machine for a particular job.

For starting and stopping the rotation of the work, a fluid-operated mechanism is utilized. It will be remembered that the shaft 149, which drives the driving head 144 (see Figure 6^A) is driven by a belt 153 from a cone pulley which is mounted on the swinging frame 156, as indicated in Figure 2, so that, when the frame is lifted, power is no longer transmitted to the work-driving shaft and the work thereupon ceases rotation. The arm 161, which is connected to the swinging frame 156, is provided with a lug or ear 289 which is located directly above a plunger 290 arranged in a cylinder 291 which is bolted to the end of the bed. In the lower end of this cylinder, there is a port 292 which is connected by a pipe or conduit 293 with the conduit 255, as shown conventionally in Figure 28. The port 292 is formed as a valve seat, against which a valve 294 is pressed yieldingly by a spring 295 both placed in a socket in the lower end of the cylinder. This valve member 294 is chambered as at 296 and it has a small vent 297 leading lat-

erally therefrom. When the fluid under pressure is delivered through the conduit 293 and the port 292, the valve 294 is forced thereby to the left (in Figure 28) so that the piston or plunger 290 is raised and thereby carries the lever 161 from the full line position to the dotted line position in Figure 2 to loosen the belt 153 and prevent further transmission of power to the driving head by which the work is rotated. This occurs when the main valve 251 has been moved to a position to permit the fluid to enter the piston 281 and move the piston from its extreme left position to the neutral position shown in Figure 28. When the valve is in this neutral position, even though the liquid be cut off from the conduits 255, it cannot escape therefrom, and consequently the plunger 290 remains in its elevated position. When the operator, however, moves the main valve to start the feed of the work carrier, the conduit 255 is connected with the return conduit 263, and the liquid is now permitted to flow out of the cylinder 291 by the weight of the plunger 290 and the lever 161 and the swinging frame 156. It is desirable, however, that the work should be clamped by the work centers before the work is started in rotation, and it is for this reason that the valve 294 is provided with the small vent 297. As soon as the pressure on the piston or plunger 290 is released, the spring 295 closes the valve 294, and thereafter the liquid can escape from the cylinder 291 only through the small vent 297. Therefore, the downward stroke of the plunger is retarded a sufficient length of time to permit the centers to engage the work firmly and properly before the swinging frame reaches its lowermost position to tighten the belt 153 and cause the transmission of power to the work-driving head.

In actual operation, the operator manually holds the bar to be ground between the work centers and shifts the main valve in the manner previously described. This causes the feeding of the work carrier to start slowly and the operation of the tail center and its supporting plunger to cause the work to be gripped, and, when this has been accomplished, the driving head is started in operation, all automatically by the mechanism previously described. After the grinding has been completed and the work carrier has been withdrawn to its initial starting position, the feeding mechanism is thrown out of operation. The rotation of the work ceases and the movable tail center is moved into a position to release the work soon after the work carrier starts its release.

Dressing mechanism for the grinding wheels.

One of the salient features of the present machine is the truing mechanism for the

grinding wheels. The dressing tool is mounted in a swinging arm which is normally in inactive position but which may be swung downwardly so as to bring the dressing tool into operative relation to the grinding wheel. The dressing tool is indicated at 300 and it is adjustably clamped in a swinging arm 301, the hub 302 of which is rigidly secured to the bar 53, to which reference has previously been made. This bar is adapted to oscillate in bushings 303, 304, placed in bearings in the upright standards 51, 52, and is also adapted to slide therein. To protect the bearings, the bar 53 is provided with two sets of telescoping sleeves 305, 306. In each case, the sleeve 306 is screwed into the threaded aperture in the upright or standard, and the sleeve 305 can slide back and forth with the bar 53. At one end, the bar 53 has a weighted arm 307 keyed thereto, and between the hub of this arm and a shoulder 308 on the bar there is placed a second weighted lever 309. The hubs of these two levers have spaced shoulders 310, 311, adapted to engage when one has moved to a limited extent relatively to the other. Normally, when the dressing tool is not in operation, the weighted arms 307, 309 hang downwardly and hold the arm 301 substantially upright in the position shown in Figures 1 and 3. The operator, however, standing in front of the machine, may manually grasp the arm and swing it forwardly and downwardly. During the first portion of this movement, the partial rotation of the bar 53 swings the weighted arm 307 rearwardly and upwardly until the shoulders 310, 311 on the hubs of the two weighted arms engage, and thereafter the weighted arm 309 will be swung rearwardly and upwardly until it reaches the position shown in Figure 14, in which position the dressing tool is engaged with the grinding wheel. The bar 53 may now be reciprocated under the control of the operative. Any suitable mechanism for effecting its reciprocation is employed, but preferably, inasmuch as I employ other mechanism which is controlled by fluid pressure, I also utilize this pressure for moving the dressing tool bar. To this end, a casing 312 is screwed to the bearing at the upper end of the upright 52. The end of the bar 53 is enlarged to form a cylinder 313, the inner end of which may be closed by a plug 314. A stationary piston 315 is located in the cylinder thus provided and a stationary extension or piston rod 316 extends through a stuffing box located in the head 317 at the end of the cylinder. The outer end of this piston rod is screwed into the end of the casing 312. Conduits 318, 319 extend through the piston rod, the former connecting with the left-hand end of the cylinder and the latter connecting with the right-hand end of the cylinder, as best

shown in Figure 6. When the fluid is delivered through the conduit 318, the piston being stationary, the entire bar 53 is moved to the left, and, of course, when fluid is delivered through the conduit 319, the bar 53 is moved to the right so that the dressing tool may be caused to traverse the face of the grinding wheel. Suitable pipes 320, 321 connect the conduits 318, 319, respectively, with conduits indicated at 322, 323 formed in an extension of the pump casing 242 as best shown in Figures 9 and 28. From the main pipe line 249 from the pump extends a conduit 324 to a port 325. The extension 326 of the pump casing is formed with a tubular socket in which these several ports communicate, and within the socket there is placed a sliding valve 327. The conduit 323 terminates in a port 328, whereas the conduit 322 terminates in a port 329. Exhaust ports 330, 331, which communicate with a conduit 332 leading to the main exhaust pipe 263, permit the escape of liquid back to the main reservoir 240. The valve 327 is provided with a recess or duct 335, so that, by moving it in one direction or the other, fluid may be admitted to either the port 329 or the port 328, and thence up through the pipes 321, 320, to move the bar 53 to the left or to the right (as in Figure 6) as the case may be. The valve also has the two peripheral grooves 336, 337 by which the ports 328, 329 may be placed in communication with the ports 331, 330, respectively, so that the exhaust fluid from the cylinder 313 in the bar 53 may return to the reservoir or tank. The valve 327 is manually reciprocated. Ordinarily it is held in the neutral position shown in Figure 9. A pin 338, which is screwed into the valve, extends through a slot 339 in the valve casing and is provided with a movable handle 340. Normally the foot of this handle rests between the two stop pins 341, 342, and thereby the valve is held in its neutral position against longitudinal movement. The operator, however, may, by grasping the handle 340, lift it sufficiently to free its foot from the pins 341, 342, and may thus move the valve in one direction or the other to cause the corresponding movement of the bar 53 and the dressing tool carried thereby.

When the truing tool is operating on the grinding wheel, it may be guided in any desired path by the use of a control bar or template which is preferably supported on the work carrier. Referring now to Figures 3, 5, and 23 to 27 inclusive, it will be noted that, on the front side of the longitudinal bar 57 which forms a portion of the work carrier, there is an upright longitudinal flange 350, and in the angle formed by this flange there are secured two blocks 351, 352, which constitute portions of a holding mechanism for the control bar or template. In

these blocks there are arranged two center pins 353, 354. The block or holder 351 is split so that the center pin 353 may be clamped in place by the screw 355 after the center pin has been adjusted to proper position. The center pin 354 is seated in a socket in the holder 352, which is also split (as shown in Figure 25) so that the split portions may be drawn together by a screw 356 to clamp the center pin. A spring 357 is seated in the socket and bears against the shoulder on the center pin, as best shown in Figure 23. By slightly loosening the clamp, the head 358 on the end of the center pin may be grasped and the center pin moved to the right to release the control bar which was previously engaged thereby. A control bar of any suitable form may be placed in the holders and locked rigidly in place so as to guide the dressing tool arm as it is reciprocated axially of the bar 53. The control bar may be straight, shouldered, convexly or concavely curved, or tapered, as may be desired. Preferably, although not necessarily, it is circular in cross section. I have shown in Figure 23 a control bar which is indicated at 359 and which has centering recesses 360, 361 at its ends to receive the center pins 353, 354. The ends of the control bar rest on flat faces 362, 362 (shown in plan view in Figure 23) on which the center pin holders 351, 352 are secured, and the sides of the end portions of the control bar rest against abutment screws 363, 364, which are passed through the flange 350 of the work carrier. The abutment screw 363 has a relatively coarse thread and it is locked in position by a set screw 365. The screw 364 has a fine lead and is screwed into a threaded sleeve 366 inserted in a flange 350. The end of this screw has a knurled head 367 by which it may be rotated. In practice, the center pin 354 being drawn to the right in Figure 23, the control bar is placed in position as shown, so that its ends rest on the flat faces 362 and its sides against the screws 363, 364, after which the center pin 358 is released by the operator and is forced by its spring into engagement with the socket 361 at the end of the bar. Each end of the bar is thus engaged by a three-point bearing and is held accurately in position. The clamping screws 355, 356 may be set tight to hold the center pins in position. Ordinarily the pressure of the spring 357 is sufficient to cause the center pins to grip the control bar and hold it accurately in position without tightening the clamping screw 356. The holding mechanism for the control bar is capable of an exceedingly fine adjustment without distorting the control bar. The swinging arm 301, which carries the dressing tool 300, is formed at its end with a bearing 369 in which a thrust pin 368 is arranged so that the end of the thrust pin

may project beyond the arm and be brought against the rear side of the control bar 359, as shown in Figure 14. The arm is of such length that it can be swung over or past the 5 control bar, and, to permit this, the pin 368 must be partially withdrawn so that its projecting end is substantially flush with the end of the arm. The pin is provided with a knurled head 370 which may be grasped 10 by the operator for this purpose. The bearing for this thrust pin is split, as shown in Figure 2, and a clamping screw 371 may be used to draw the portions of the bearing together to clamp the thrust pin in either its 15 advanced or retracted position. When the operator desires to dress the grinding wheel, the arm 301 is moved from the position shown in Figure 3 forwardly and downwardly, and the thrust pin 368 is retracted 20 to permit the arm to pass the control bar 359. Thereafter the operator forces the thrust pin downwardly so that its end engages the rear side of the control bar. The operator then by hand operates the feed 25 mechanism of the work carrier to bring the dressing tool into engagement with the grinding wheel, and, by manipulation of the valve handle 340, causes the dressing tool bar 53 to be reciprocated, whereby the dressing 30 tool traverses the face of the grinding wheel. The control bar corresponds to the shape of the finished work so that the wheel is dressed to impart that shape to a new piece of work. For example, in Figures 19 to 22 inclusive, 35 I have illustrated different pieces of work, and the control bars for dressing the wheels, by which these pieces of work are finished, correspond to the pieces as illustrated. Where the grinding wheel consists of several 40 sections which vary in diameter, as for example in Figures 7 and 20, there are shoulders between the several sections, and the thrust pin on the dressing tool arm could not slide back and forth on the shouldered control bar. I provide, however, a shouldered 45 control bar in which this may be accomplished. In Figures 23 and 24, I have shown the control bar as being provided with the three different diameters *a*, *b* and 50 *c*, separated by the shoulders *d* and *e*. In the smaller section *c* and in the intermediate section *b*, I introduce pins 372, 373, which are semi-cylindrical. The end of 55 each pin is flush with the next section of a larger diameter, but it is also provided with inclined faces 374, 374, by which the end of the thrust pin may be guided from the periphery of one section *c* for example, to the next section *b* for example, and thence to 60 the section *a*. To accomplish this result, assuming that the thrust pin 368 is moving to the left in Figure 23, it continues this movement until it engages the shoulder *e*. The operator then by hand rotates the control bar about its axis to bring the beveled 65 pin 372 under the thrust pin and thus thrust it rearwardly far enough until it can ride on the section *c* of the control bar. The thrust pin then continues its movement to the left until it engages the shoulder *d*, 70 whereupon the operator again rocks the control bar to bring the pin 373 under the thrust pin and again swing the thrust pin rearwardly far enough until it can ride on the section *a*. When the thrust pin is moving in the opposite direction or to the right, it may drop off of the shoulder to the next 75 diametrically smaller section without doing any damage. It will be remembered that the dressing tool bar 53 is moved by fluid pressure from the pump, but, inasmuch as the relief valve mechanism previously described is included in the hydraulic system, the thrust pin 368 may engage one of the shoulders *d* or *e* and be arrested without 80 damage. A very decided advantage is thus achieved by the employment of a yielding mechanism for operating the dressing tool. 85

Water supply mechanism.

In addition to the foregoing features, the machine is provided with mechanism for supplying water to the grinding tool, and provision is made by which the supply of water is automatically cut off when the 90 grinding operation ceases. The hollow bed serves as a reservoir for the water, as shown in Figure 5, from which the water is forced by any suitable pump to the nozzle from which it is delivered against the grinding 95 wheel. In Figure 2, a pump is indicated as a whole at 375, the casing being bolted to the rear of the bed and communicating with the reservoir chamber 376 therein. The pump shaft 377 is shown as being driven by 100 a cross belt 378 from a pulley 379 on the main drive shaft 125. From the pump, a pipe 380 extends upwardly and thence forwardly, and terminates in a nozzle 381 so as to deliver a stream of water on the grinding wheel near the line of contact therewith of the work and in front of the water guard 101 which partially encloses the grinding wheel. Water, which flows or drips from 105 the wheel and from the guard 109, drops down to the upper portion of the bed which has the transverse partition 382 to provide an initial receptacle or catch basin 383 located above the main reservoir 376. The 110 partition 382 has an outlet 384 through which the water may run back into the main reservoir 376 so as to be again circulated by the pump through the water pipe and its delivery nozzle. It is desirable, 115 however, that the grit and particles of metal removed by abrasion should be separated from the water, and for this purpose I find it desirable at times to employ a settling tank 385, which is portable and which is 120 shown as provided with supporting wheels 125 130

386. The rear wall of the bed is formed to provide a recess 387 into which the settling tank may be partially inserted, as shown in Figures 2 and 5, and the settling tank has 5 a lip 388 which may be introduced below the outlet 384 so that the water will be diverted thereby into the settling tank. A spout 389 permits the overflow from the settling tank to flow back into the main 10 reservoir or supply tank 376. By the provision of the settling tank, the foreign particles of grit and metal, which flow with the water into the tank, are permitted to settle therein and substantially clear water is delivered back into the reservoir in the bed 15 of the machine. The water pipe is provided with a controlling or cut-off valve 390, the valve member of which may be moved to open and closed position by an elongated 20 valve stem 391 which extends through the upper portion of the bed of the machine and through the front wall thereof, as shown in Figures 1 and 11. The front end of this 25 valve rod or valve stem is indicated at 392 and is coupled with the stem 391 by a coupling pin 393.

On the extreme front end of the section 392, there is placed a handle 394 which may be grasped by the operator to rock the valve 30 stem and open or close the valve. Mounted loosely on the projecting end of the shaft or rod section 392, there is a bell-crank, one arm of which is indicated at 395 and the other arm at 396 (see Figures 11 and 17). 35 The arm 395 may be interlocked with the handle 394 by a spring pressed locking bolt 3961 entering a socket 397 in the arm 395. The projecting end of the locking bolt has a knob or head 398 which may be grasped 40 by the operator to release the handle 394 and permit the valve to be opened and closed at will without stopping the rotation of the work. The other arm 396 of the bell-crank is adapted to be actuated automatically to open or close the valve in the 45 water pipe. Connections are provided so that, when the rotation of the work ceases, the cut-off valve is automatically closed, and is then again automatically opened when the 50 rotation of the work begins again. The lever 161, which controls the transmission of power to the work, has a laterally projecting lug 399 to which is pivoted one end of a link 400, the other end of which is pivoted to a block 401 arranged to slide on the arm 396 of the bell-crank lever. When the plunger 290 is raised by fluid pressure and the lever 161 is carried upwardly with it, the bell-crank is rocked about its axis by the 55 connections 400, 401, to rotate the valve and cut off the supply of water. I preferably employ a fan pump for feeding the water, so that, when the valve in the water pipe 60 is closed, the pump runs idly or without

forcing water into the pipe against the back 65 pressure therein. When the plunger 290 drops and power is again transmitted to the driving head for the work, the water valve is automatically opened and water is delivered 70 to the grinding wheel.

Additional features.

I have stated that, instead of employing a stationary head center and a rotary driving head, I may adopt an equivalent construction in which the head center rotates. Such a construction is shown in Figure 8. In this case, the spindle, which is indicated at 410, is arranged to rotate in its bearing so as to rotate the center pin 411 with it. In this case, the spindle is illustrated as being mounted in anti-friction bearings 412, 413 in a sleeve 414. On the end of the spindle is secured a face or chuck plate 415 which corresponds to the driving plate 144 80 in Figure 6^A. This plate has an internally toothed flanged rim which is driven by the gear 148 on shaft 149. In fact, in my machine, the spindle 142 in Figure 6^A may be withdrawn, and the sleeve 414 and the spindle 410 inserted in its place, the two mechanisms thus being interchangeable. It has, however, long been a common expedient in 85 grinding machines, as in other metal-working machines, to employ at will either a stationary head center and a rotating driving head or plate, or a rotary center and a driving head or chuck plate.

If it be desired to employ, in lieu of a fluid-operated control for the feeding 100 mechanism by which the work carrier is fed towards and from the grinding wheel, a mechanically-operated mechanism, I may employ one such as illustrated in Figures 29 and 30. In this case, the feed box, which is indicated at 420, is provided with the double worm shaft 421 which corresponds to the equivalent shaft 228 in Figure 9, and the shaft 421 is driven in the same manner as said shaft 228. In order that it may be reciprocated, however, to bring one or the other of the worms 422, 423 into engagement with the worm wheel 234, or be brought to a neutral position, a mechanical mechanism is employed which comprises the following 105 elements. Within the feed box and below the shaft 421 there is a sliding shaft 424, to which is fixed a carriage 425 to slide therewith. The upper end of this carriage is connected by a yoke to the worm shaft 421, said yoke playing between two collars 426, 427 pinned to said shaft. On the lower end of the carriage 425 there are two lugs 428, 429 which embrace a truck 430 on an arm or lever 431 which is pivoted at 432. The free end of said arm has pivoted thereto a segmental weight 433 which is adapted to rock 110 between shoulders 434, 435 on said arm. 115

- When the rotation of the wheel 234 is arrested, assuming that it is rotating in the direction of the arrow in Figure 29, the continued rotation of the shaft 421 moves the 5 said shaft and the carriage 425 to the left, and thereby one of the lugs 429 engages the truck 430 so as to swing the arm 431 to the left. As the arm approaches a vertical position and before the worm 422 has left 10 the worm wheel, a lug 436 engages one of two loosely pivoted crossed fingers 437, 437, and the weight 433 is thrown in the same direction as the travel of movement of the lever 431 so as to overbalance the lever and 15 swing it to the left and thereby carry the carriage 425 far enough to the left to bring the other worm 423 into mesh with the worm wheel 234. Ordinarily it is desired, during this particular part of the operation 20 of the automatic feeding mechanism in which the reverse feeding worm 422 is moved out of engagement with the worm wheel 234, that the shaft 421 should be arrested in a neutral position, and for this 25 purpose I employ a pivoted latch 438 which normally rests on the side of the carriage and which has a shoulder 439 to engage the carriage and arrest it when the shaft 421 is in neutral position. This latch is pivoted 30 at 440, and, by lifting it, the operator permits the weight 433 to drop downwardly to the left so as to shift the shaft 421 still further to the left and bring the feeding worm 423 into engagement with the worm 35 wheel 234. Thereafter the continued rotation of the shaft 421 causes the work carrier to be fed forwardly until the worm stop 213 engages the pin 216 and arrests the forward feeding of the work carrier. Thereupon, as the worm wheel 234 is then held 40 against further rotation, the continued rotation of the shaft 421 causes the worm 423 to be fed along the worm wheel to the right so as to move the carriage 425 to the right 45 and thereby one of the lugs 428 engages the truck 430 so as to swing the weight 433 to the right. As the arm approaches a vertical position, and before the worm 423 has left the worm wheel, a lug 441 engages one of 50 the fingers 437 and the weight is thrown in the same direction as the travel or movement of the lever 431 so as to overbalance the lever and swing it to the right to bring the carriage far enough to the right to bring 55 the other worm 422 into mesh with the worm wheel 234.
- If desired, the two feeding worms, for the forward feed and the reverse feed for withdrawing the carriage, may have teeth at different pitches so that the withdrawing movement of the carriage may be at a higher rate of speed than the feeding movement. Inasmuch as both of these worms must engage the same worm wheel, the latter is 60 formed with teeth of both right-hand and left-hand leads of the proper pitch, as shown, for example, in the development of the worm wheel illustrated in Figure 15.
- From the foregoing description of the machine, it will be observed that the latter accomplishes the objects which I set forth in the preliminary portion of the specification.
- This tool comprises a grinding machine, a bed, and, mounted thereon and attached thereto, a grinding wheel carrier and a work carrier, one of which, by means of bar or trunnions slidingly and rotatably mounted on said bed, has either or both a transverse and longitudinal motion relative to the 75 other carriage. This construction, while meeting all of the requirements, in range and traverse, permits the elimination of one sliding member usually employed, and therefore presents a construction in which a more 80 direct control between the work and the grinding wheel is given,—this having a most important bearing in contributing to greater accuracy and production in the work 85 finished thereon. The machine is thus 90 adapted for grinding bars having widely different contours and diameters. There is, of course, a control bar corresponding to each finished piece of work, and interchangeable 95 grinding wheels, so that the grinding wheels may be properly dressed to operate on work corresponding to the control bar. As previously pointed out, although the grinding 100 wheel may be adjusted in reference to the work, yet, when the wheel carriage has been 105 properly adjusted, it requires no further movement until the wear of the wheel makes it necessary to reset it, or it is desirable to tool the machine for work of a different diameter. One of the manifest advantages 110 of the machine is, as previously pointed out, that, by using a broad faced grinding wheel formed in sections of different diameters, an entire bar having portions of different 115 diameters may be finished or ground at one operation. This avoids handling the work more than once for the grinding operation. Furthermore this ensures accurate concentricity of different portions of the bar, 120 which is not assured when the bar is subjected to successive grinding operations.
- The use of broad face grinding wheels, either of the same or different diameters, also offers advantages in both increased output and greater accuracy in production. This is accounted for on the score of increased production by the use of wheels with grinding faces approximating the length of the work to be ground, so that an equal amount of stock may be removed simultaneously the full length of the work. It is apparent that the same amount of metal can thus be more 125 quickly removed than in the use of a narrow

grinding face ordinarily employed, which must be arranged to travel back and forth across the work to be ground at such length as is required to cut over the entire length of the work. This advantage applies both to the finishing of a long single diameter and to a combination of different diameters, but, in finishing pieces of different diameters, an added advantage is obtained from the fact that the several diameters or sizes may be finished at one operation, thereby effecting the saving of the time required to change the pieces from one machine to another, or, if one operation follows another in the same machine, the elimination of making of necessary adjustments on the grinding machine. There is also an advantage in accuracy in the finishing of several diameters at one operation, in that all surfaces thus finished are concentric and true with each other, a condition which may or may not be so, as the work is moved in and out of the machine in making the several operations one at a time. Even though a bar is to be ground so as to have the same diameter from end to end, I find it desirable to employ a sectional grinding wheel, as the reciprocation of the work makes it possible to prevent the formation of corrugations or irregularities on the periphery of the work. By employing relatively narrow sections, they can be combined together in axial relation to produce a grinding tool having the breadth of face desired. For instance, although in Figure 7 I have shown the three sections 91, 92 and 93 of the grinding wheel, which are all clamped together to form in effect a single wheel, of different diameters, nevertheless I frequently use them when they are all of the same diameter. In Figure 19, the grinding wheel 96 is shown as being composed of three sections which are of the same diameter and in this respect different from those at 91, 92 and 93 in Figure 20.

Thus, for the machine herein described, by means of the particular design of the wheel truing member and of its control by means of a guiding or templet bar, it is possible to form wheels to specified shapes and diameters to duplicate a certain arrangement of finished surfaces on a piece of work.

As previously stated, the use of this machine in the manufacture of several different kinds of work, requires the use of a separate guide or templet bar for each job and a corresponding wheel unit, and, as from time to time it is desired to finish a number of pieces of any one kind of work, the machine is provided with a particular wheel and a control bar which in shape corresponds to the work to be ground. Particularly in the grinding of work with several diameters and shapes, it is apparent that

once the shape of the guide or templet bar has been correctly made, so that through the truing member it may so shape the wheel as to give the proper sizes on the work to be ground, it is a very short and easy matter to exchange one set of wheels and guide bars for another, and that absolute duplication of the work to be ground of the same piece at different times is automatically assured, and not dependent in a large degree upon the skill of the operator.

There is, as stated, an advantage in the use of several narrow wheels clamped together as one unit in the grinding of a single diameter of an equal length. For instance, in the grinding of a bar of twelve-inch length, I may use six two-inch width wheels clamped together, or four three-inch wheels mounted side by side. The use of a limited reciprocation or longitudinal traverse for the work carrier permits the use of a wheel so mounted, as the side motion of the work serves to eliminate any marks that might be made by the joints in the grinding wheels. An economic advantage is secured in the use of narrow wheels in making up a broad face, on the score of its being unnecessary to keep in stock wheels to cover a variety of lengths of work. For instance, if there were pieces six-inch, eight-inch, ten-inch and twelve-inch length to be ground in different lots, by using one broad wheel it would be necessary to carry a wheel for each length. By the use of the narrow wheels, say of two-inch and three-inch width, a combination of different widths can be used to make up the total length needed, making a great deal smaller the wheel investment required. Also, due to the usual method of building up the abrasive material, it is easier to construct a narrow face grinding wheel without variation in the hardness or abrasive qualities of the grinding material throughout, than by the use of one wheel of greater face and area.

Having thus explained the nature of my said invention and described a way of making and using the same, although without attempting to set forth all of the forms in which it may be made or all of the modes of its use, what I claim is:—

1. A grinding machine comprising a bed, a tool carriage thereon, a grinding wheel journaled on said carriage, a work carrier movable about an axis substantially parallel to the axis of the grinding wheel, and power-actuated mechanism for automatically swinging said work carrier about its axis to advance the work from a remote position to and against the grinding wheel and then to withdraw the work from said grinding wheel to such remote position.

2. A grinding wheel comprising a bed, a grinding wheel supported thereon, a work carrier pivotally supported by the bed and

- movable about its axis toward and from the grinding wheel, mechanism for automatically feeding said work carrier to advance the work to and against the grinding wheel and automatically withdrawing said work carrier, and means by which the work may be manually operated toward or from the grinding wheel.
3. A grinding machine comprising a bed, a swinging carrier, a work support for rotating the work and a grinding wheel mounted on the first-mentioned instrumentalities, mechanism by which the work and the grinding wheel are continuously rotated while the wheel is in contact with the work, and automatic mechanism for automatically advancing and withdrawing said carrier about its axis, and including a manually-operated member by which the carrier may be moved during and without affecting the operation of said automatic mechanism.
4. A grinding machine comprising a bed, a carrier, a grinding wheel and a work support mounted on said bed and carrier, and automatically operated yielding means for feeding said carrier.
5. A grinding machine comprising a bed, a swinging carrier, a nut and screw device for moving said carrier, means for automatically operating said device to feed the carrier in opposite directions alternately, and means for manually operating said device during the automatic operation thereof to vary the speed of movement of the carrier.
- 35 6. A grinding machine comprising a bed, a carrier movable relatively thereto, a rotary nut supported by the bed, a screw engaged therewith and movable thereby for feeding the carrier, automatic mechanism for rotating the nut, and manual means for rotating the nut independently during the operation of said automatic mechanism.
7. A grinding machine comprising a bed, a carrier movable relatively thereto, a rotary nut supported by the bed, a screw engaged therewith and movable thereby for feeding the carrier, automatic mechanism for rotating the nut, and a hand wheel frictionally connected with the automatic mechanism and positively connected with said nut for rotating the nut.
8. A grinding machine comprising a bed, a grinding wheel, a work support, a carrier for one of the last-mentioned instrumentalities, a screw and a nut of which one is engaged with the bed and the other with the carrier, one of said elements being rotatable and the other fixed against rotation, and a manually-adjustable member having an intermeshing engagement with and carried by said rotatable element and bodily revoluble relatively thereto about the axis thereof.
9. A grinding machine comprising a bed, a grinding wheel, a carrier, a nut and screw device for feeding said carrier, a stationary stop, and a settable element on said device for positively engaging said stop and stopping the feeding movement of said carrier.
10. A grinding machine comprising a bed, a grinding wheel, a carrier, a nut and screw device for feeding said carrier, a stationary stop, a settable element on said device for positively engaging said stop and stopping the feeding movement of said carrier, and intermeshing means on said element or device for adjusting or setting said element.
11. A grinding machine comprising a bed, a carrier, a screw and a nut for feeding said carrier, one of said elements being rotatable relatively to the other, the rotatable element being peripherally toothed, and a settable member carried by said rotatable element and intermeshing with the teeth on said element.
12. A grinding machine comprising a bed, a carrier, a screw and a nut for feeding said carrier, one of said elements being rotatable relatively to the other, the rotatable element having peripheral worm teeth, a collar rotatable about the axis of said rotatable element, a settable member on said collar having helical teeth intermeshing with said worm teeth, and means for rotating said settable member to move it bodily about the axis of said rotatable element.
13. A grinding machine comprising a bed, a carrier, a screw and a nut for feeding said carrier, one of said elements being rotatable relatively to the other, yielding means for rotating said rotatable element, a relatively stationary stop, and a complemental settable stop rotatable with said rotatable element into engagement with the stationary stop to effect the cessation of feed of said carrier.
14. A grinding machine comprising a bed, a carrier, a screw and a nut for feeding said carrier, one of said elements being rotatable relatively to the other, yielding means for rotating said rotatable element, a relatively stationary stop, a complemental settable stop rotatable with said rotatable element into engagement with the stationary stop to effect the cessation of feed of said carrier, and means for adjusting said settable stop relatively to said rotatable element about the axis thereof.
15. A grinding machine comprising a bed; a grinding wheel; a work support; a carrier for effecting a relative movement of the grinding wheel and work support; and means for feeding said carrier including a screw element and a nut element of which one is rotatable relatively to the other, a hand wheel positively connected to the rotatable element, a member frictionally connected to said hand wheel, automatic means for rotating said member, and positive stop mechanism for stopping the rotation of said rotatable element.
16. A grinding machine comprising a bed;

- a grinding wheel; a work support; a carrier for effecting a relative movement of the grinding wheel and work support; and means for feeding said carrier including a screw element and a nut element of which one is rotatable relatively to the other, means for rotating said element to feed the work, a worm wheel fixed to said element to rotate therewith, a worm engaged with said worm wheel to rotate therewith, and means for rotating said worm to revolve it about said worm wheel.
17. A grinding machine comprising a bed; a grinding wheel; a work support; a carrier for effecting a relative movement of the grinding wheel and work support; and means for feeding said carrier including a screw element and a nut element of which one is rotatable relatively to the other, means for rotating said element to feed the work, a worm wheel fixed to said element to rotate therewith, a worm engaged with said worm wheel to rotate therewith, means for rotating said worm to revolve it about said worm wheel, a rotatable member in which said worm is journaled, and a stop located in the path of said worm, said worm being rotatable to adjust it about said worm wheel relatively to said rotatable element.
18. A grinding machine comprising a bed, a grinding wheel, a work support, a carrier for effecting a relative movement of said grinding wheel and work support, a relatively stationary stop for positively stopping the feeding movement of the carrier, and automatic mechanism for feeding the carrier until its movement is stopped and then automatically retracting said carrier.
19. A grinding machine comprising a bed, a grinding wheel, a work support, a carrier for effecting a relative movement of said grinding wheel and work support, a relatively stationary stop for positively stopping the feeding movement of the carrier, and automatic mechanism for feeding the carrier until its movement is stopped and then automatically retracting said carrier, said mechanism including driving members arranged respectively to feed and to withdraw said carrier in alternation, and means acting automatically on the cessation of feeding movement of said carrier to render one of said driving members active and the other inactive.
20. A grinding machine comprising a bed, a grinding wheel, a work support, a carrier for effecting a relative movement of said grinding wheel and work support, a relatively stationary stop for positively stopping the feeding movement of the carrier, and automatic mechanism for feeding the carrier until its movement is stopped and then automatically retracting said carrier, said mechanism comprising a worm wheel, a screw and nut device operated thereby, and separate worms adapted for alternate engagement with the worm wheel, said parts being so constructed and arranged that one of said worms is engaged with the worm wheel for feeding the carrier until the advance thereof is stopped, whereupon the other worm is engaged with the worm wheel to retract the carrier.
21. A grinding machine comprising a bed, a grinding wheel, a work support, a carrier for effecting a relative movement of said grinding wheel and work support, a screw element and a nut element for moving said carrier, of which one is rotatable relatively to the other, a stationary stop, a complementary stop rotatable concurrently with the rotatable element, and automatic mechanism for rotating said rotary element in one direction until it is stopped by the engagement of said stops and then rotating it in the opposite direction.
22. A grinding machine comprising a bed, a grinding wheel, a work support, a carrier for effecting a relative movement of said grinding wheel and work support, a screw element and a nut element for moving said carrier, of which one is rotatable relatively to the other, a stationary stop, a complementary stop rotatable concurrently with the rotatable element, a worm wheel for rotating said rotatable element, and a driving shaft having oppositely threaded worms for alternate engagement with the worm wheel and capable of endwise movement for causing such alternate engagement whereby, when the rotatable element is stopped by the engagement of said stops, the continued rotation of said driving shaft causes it to be moved longitudinally to disengage the operating worm from the worm wheel.
23. A grinding machine comprising a bed, a grinding wheel, a work support, a carrier for effecting a relative movement of said grinding wheel and work support, a screw element and a nut element for moving said carrier, of which one is rotatable relatively to the other, a stationary stop, a complementary stop rotatable concurrently with the rotatable element, a worm wheel for rotating said rotatable element, a driving shaft having oppositely threaded worms for alternate engagement with the worm wheel and capable of endwise movement for causing such alternate engagement whereby, when the rotatable element is stopped by the engagement of said stops, the continued rotation of said driving shaft causes it to be moved longitudinally to disengage the operating worm from the worm wheel, and automatic means for further moving said shaft for bringing the other worm into engagement with the worm wheel.
24. A grinding machine comprising a bed, a grinding wheel, a work support, a carrier for effecting a relative movement of said

- grinding wheel and work support, a screw element and a nut element for moving said carrier, of which one is rotatable relatively to the other, a stationary stop, a complementary stop rotatable concurrently with the rotatable element, a worm wheel for rotating said rotatable element, a driving shaft having oppositely threaded worms for alternate engagement with the worm wheel and capable of endwise movement for causing such alternate engagement whereby, when the rotatable element is stopped by the engagement of said stops, the continued rotation of said driving shaft causes it to be moved longitudinally to disengage the operating worm from the worm wheel, and manually-controlled means for moving said shaft endwise.
25. A grinding machine comprising a bed, a grinding wheel, a work support, a carrier for effecting a relative movement of said grinding wheel and work support, a screw element and a nut element for moving said carrier, of which one is rotatable relatively to the other, a stationary stop, a complementary stop rotatable concurrently with the rotatable element, a worm wheel for rotating said rotatable element, a driving shaft having oppositely threaded worms for alternate engagement with the worm wheel and capable of endwise movement for causing such alternate engagement whereby, when the rotatable element is stopped by the engagement of said stops, the continued rotation of said driving shaft causes it to be moved longitudinally to disengage the operating worm from the worm wheel, automatic means for further moving with the worm wheel, and manual means for controlling the endwise movement of said shaft.
30. A grinding machine comprising a bed, a grinding wheel, a work support, a carrier for effecting a relative movement of said grinding wheel and work support, a screw element and a nut element for moving said carrier, of which one is rotatable relatively to the other, a stationary stop, a complementary stop rotatable concurrently with the rotatable element, a worm wheel for rotating said rotatable element, a driving shaft having oppositely threaded worms for alternate engagement with the worm wheel and capable of endwise movement for causing such alternate engagement whereby, when the rotatable element is stopped by the engagement of said stops, the continued rotation of said driving shaft causes it to be moved longitudinally to disengage the operating worm from the worm wheel, automatic means for further moving with the worm wheel, and manual means for controlling the endwise movement of said shaft.
35. A grinding machine comprising a bed, a grinding wheel, a work support, a carrier for effecting a relative movement of said grinding wheel and work support, a screw element and a nut element for moving said carrier, of which one is rotatable relatively to the other, a worm shaft for rotating said movable element, a longitudinally movable driving shaft having worms of opposite pitch for rotating said worm wheel in opposite directions, and mechanism by which said shaft may be moved longitudinally to bring one or the other of said worms into engagement with said worm wheel.
40. A grinding machine comprising a bed, a grinding wheel, a work support, a carrier for effecting a relative movement of said grinding wheel and work support, a screw element and a nut element for moving said carrier, of which one is rotatable relatively to the other, a driving shaft rotatable in only one direction, and mechanism operated by said shaft for rotating said rotatable element in opposite directions to feed and withdraw said carrier.
45. A grinding machine comprising a bed, a grinding wheel, a work support, a carrier for effecting a relative movement of said grinding wheel and work support, a screw element and a nut element for moving said carrier, of which one is rotatable relatively to the other, means for rotating said rotatable element in opposite directions, and fluid-operated means controlling the operation of the last-mentioned means.
50. A grinding machine comprising a bed, a grinding wheel thereon, a work carrier movable toward and from the grinding wheel to feed the work to and retract it from the grinding wheel, a work support on said work carrier comprising members for engaging the opposite ends of a piece of work, and automatic mechanism for causing said members to engage said work when the work carrier is in retracted position.
55. A grinding machine comprising a bed, a grinding wheel thereon, a work carrier movable toward and from the grinding wheel to feed the work to and retract it from the grinding wheel, a work support on said work carrier comprising members for engaging the opposite ends of a piece of work, and automatic mechanism for causing said members to engage and release the work when the work carrier is in retracted position.
60. A grinding machine comprising a bed, a grinding wheel, a work support, a carrier for effecting a relative movement of said grinding wheel and work support, a screw element and a nut element for moving said carrier, of which one is rotatable relatively to the other, a driving shaft rotatable in only one direction, and mechanism operated by said shaft for rotating said rotatable element in opposite directions to feed and withdraw said carrier.
65. A grinding machine comprising a bed, a grinding wheel, a work support, a carrier for effecting a relative movement of said grinding wheel and work support, a screw element and a nut element for moving said carrier, of which one is rotatable relatively to the other, means for rotating said rotatable element in opposite directions, and fluid-operated means controlling the operation of the last-mentioned means.
70. A grinding machine comprising a bed, a grinding wheel, a work support, a carrier for effecting a relative movement of said grinding wheel and work support, a screw element and a nut element for moving said carrier, of which one is rotatable relatively to the other, means for rotating said rotatable element in opposite directions, and fluid-operated means controlling the operation of the last-mentioned means.
75. A grinding machine comprising a bed, a grinding wheel thereon, a work carrier movable toward and from the grinding wheel to feed the work to and retract it from the grinding wheel, a work support on said work carrier comprising members for engaging the opposite ends of a piece of work, and automatic mechanism for causing said members to engage said work when the work carrier is in retracted position.
80. A grinding machine comprising a bed, a grinding wheel thereon, a work carrier movable toward and from the grinding wheel to feed the work to and retract it from the grinding wheel, a work support on said work carrier comprising members for engaging the opposite ends of a piece of work, and automatic mechanism for causing said members to engage and release the work when the work carrier is in retracted position.
85. A grinding machine comprising a bed, a grinding wheel thereon, a work carrier movable toward and from the grinding wheel to feed the work to and retract it from the grinding wheel, a work support on said work carrier comprising members for engaging the opposite ends of a piece of work, and automatic mechanism for causing said members to engage and release the work when the work carrier is in retracted position.
90. A grinding machine comprising a bed, a grinding wheel thereon, a work carrier movable toward and from the grinding wheel to feed the work to and retract it from the grinding wheel, a work support on said work carrier comprising members for engaging the opposite ends of a piece of work, and automatic mechanism for causing said members to engage and release the work when the work carrier is in retracted position.
95. A grinding machine comprising a bed, a grinding wheel, a work support, a carrier on which said work support is mounted for effecting a relative movement of the work support and the grinding wheel, mechanism for automatically feeding said carrier, and automatic mechanism for causing said work support to engage and release the work.
100. A grinding machine comprising a bed, a grinding wheel, a work support, a carrier on which said work support is mounted for effecting a relative movement of the work support and the grinding wheel, mechanism for automatically feeding said carrier, and automatic mechanism for causing said work support to engage and release the work.
105. A grinding machine comprising a bed, a grinding wheel, a work support, a carrier on which said work support is mounted for effecting a relative movement of the work support and the grinding wheel, mechanism for automatically feeding said carrier, and automatic mechanism for causing said work support to engage and release the work.
110. A grinding machine comprising a bed, a grinding wheel, a work support comprising members for engaging the opposite ends of a piece of work, automatic mechanism for causing said members to engage said work, and automatic mechanism for starting and stopping the rotation of the work-supporting members.
115. A grinding machine comprising a bed, a grinding wheel, mechanism for holding and rotating the work, and mechanism for automatically controlling the starting and stopping of the work-rotating mechanism.
120. A grinding machine comprising a bed, a grinding wheel, a work support including a movable center, and means for automatically moving said center into engagement with the work.
125. A grinding machine comprising a bed, a grinding wheel, a work support including oppositely arranged centers for engaging the work, and automatic mechanism for causing said centers to engage and release the work.
130. A grinding machine comprising a bed,

- a grinding wheel, a work support including oppositely arranged centers for engaging the work, automatic mechanism for causing said centers to engage and release the work, mechanism for rotating the work, and automatic mechanism for controlling the stopping and starting of said work-rotating mechanism. 5
37. A grinding machine comprising a bed, a grinding wheel, a work support including oppositely arranged centers for engaging the work, means for effecting the intermittent rotation of the work, and automatic mechanism for causing said centers to release the work when the work is at rest. 10
38. A grinding machine comprising a bed, a grinding wheel, a work support, mechanism for effecting a relative feed of the grinding wheel and work support, mechanism for effecting a rotation of the work, mechanism for causing said work support to engage and release the work, and automatic controlling devices for said mechanism, by which the work support is not in rotation 20 when the work is being engaged thereby but is in rotation when the feed is occurring. 25
39. A grinding machine comprising a bed, a grinding wheel thereon, a work carrier, a work support thereon, mechanism for feeding and retracting the said carrier, mechanism for effecting the rotation of the work, and means for automatically controlling the starting and stopping of said feed mechanism and said work rotating mechanism. 30
40. A grinding machine comprising a bed, a grinding wheel, a work support including oppositely arranged centers, automatic mechanism for effecting relative endwise movement of said centers to engage and release the work, and mechanism for effecting the rotation of the work when held by said centers and for stopping the rotation of the work prior to its release by said centers. 40
41. A grinding machine comprising a bed, a grinding wheel, a work support including oppositely arranged centers, mechanism for effecting the rotation of the work, mechanism for controlling the starting and stopping of said work rotating mechanism, and automatic mechanism for causing said centers to release the work after the rotation thereof has ceased. 45
42. A grinding machine comprising a bed, a grinding wheel, a work support including oppositely arranged centers, mechanism for effecting the rotation of the work, mechanism for controlling the starting and stopping of said work rotating mechanism, and automatic mechanism for causing said centers to release the work after the rotation thereof has ceased and to engage the work before the rotation thereof has started. 50
43. A grinding machine comprising a grinding wheel, a work support comprising oppositely arranged centers, and fluid-operated mechanism for causing one of the centers of said work support to move toward and from the other center to engage and release the work. 55
44. A grinding machine comprising a bed, a grinding wheel, a work support including a movable center, and fluid-operated means for moving said center endwise into engagement with or out of engagement with the end of the work. 70
45. A grinding machine comprising a bed, a grinding wheel, a work support including a movable center, fluid-operated means for moving said center endwise into engagement with or out of engagement with the end of the work, and means for automatically controlling the operation of said fluid-operated means. 75
46. A grinding machine comprising a bed, a grinding wheel, a work support including a movable center, a sleeve in which said center is mounted, yielding means for automatically moving said center into engagement with the work, and means on which said sleeve is supported and relatively to which said sleeve and center are longitudinally adjustable. 80
47. A grinding machine comprising a bed, a grinding wheel, oppositely arranged centers, one of said centers being adjustable relatively to the other to accommodate pieces of work of different lengths, mechanism for automatically moving one of said centers relatively to the other to engage or release the work, and a carrier having rigid pivoted arms in which said centers are supported. 85
48. A grinding machine comprising a bed, a grinding wheel thereon, a pivotally mounted work carrier having rigid supporting arms at its ends, pivot means on which the ends of said arms are mounted, work-supporting members mounted in said arms, and mechanism for moving the work carrier about its pivoted axis to feed said members toward and retract them from said grinding wheel. 100
49. A grinding machine comprising a bed, a grinding wheel thereon, a pivotally mounted work carrier having rigid supporting arms at its ends, pivot means on which the ends of said arms are pivoted, sleeves mounted in said arms, and center pins supported by said sleeves. 110
50. A grinding machine comprising a bed, a grinding wheel thereon, a pivotally mounted work carrier having supporting arms at its ends, pivot means on which the said arms are pivoted, sleeves mounted in said arms, center pins supported by said sleeves, and means on said carrier for rotating the work when held by said center pins. 115
51. A grinding machine comprising a

- bed, a grinding wheel, a work carrier having pivoted arms, and a transversely concave supporting face between said arms. 65
52. A grinding machine comprising a bed, a grinding wheel, a work carrier having pivoted arms and a supporting face between said arms, a work-engaging member, and a quill or sleeve therefor mounted in one of said arms and having a head or flange engaging said supporting face. 70
53. A grinding machine comprising a bed, a grinding wheel, a work carrier having pivoted arms, a transversely concave supporting face between said arms, a quill or sleeve mounted in one of said arms and having a segmental portion engaging said concave face, and a work-engaging member supported by said quill. 75
54. A grinding machine comprising a bed, a grinding wheel, a work carrier having pivoted arms, a transversely concave supporting face between said arms, a quill or sleeve mounted in one of said arms and having a segmental portion engaging said concave face, said quill being adjustable endwise, and a work-engaging member movable endwise relatively to said quill. 80
55. A grinding machine comprising a bed, a grinding wheel thereon, a work carrier having supporting arms pivoted to said bed, a work center carried by one of said arms, and work-rotating means mounted in the other of said arms. 85
56. A grinding machine comprising a bed, a grinding wheel thereon, a work carrier having arms pivoted to said bed, alined work-supporting members mounted in said arms respectively, one of said members being adjustable endwise relatively to the other to accommodate work of different lengths, and means for moving one of said members to engage and release the work. 90
57. A grinding machine comprising a bed, a grinding wheel thereon, a work carrier having arms pivoted to said bed, alined work-supporting members mounted in said arms respectively, one of said members being adjustable endwise relatively to the other to accommodate work of different lengths, and automatic means for actuating one of said members to engage and release the work. 95
58. A grinding machine comprising a bed, a grinding wheel, a work carrier, feeding mechanism for effecting a relative movement of the grinding wheel and the work carrier, means thereon for engaging one end of and rotating the work, a work center for engaging the other end of the work, and fluid-operated means automatically controlled by said feeding mechanism for moving said center endwise. 100
59. A grinding machine comprising a bed, a grinding wheel, a work carrier, feeding
- mechanism for effecting a relative movement of the grinding wheel and the work carrier, means thereon for engaging one end of and rotating the work, a work center for engaging the other end of the work, fluid-operated means for moving said center endwise, including a plunger supporting said center, a cylinder in which said plunger is located, and valve mechanism controlled by said feeding mechanism for controlling the admission of fluid to said cylinder. 105
60. A grinding machine comprising a bed, a grinding wheel, a work carrier, means thereon for engaging one end of and rotating the work, a work center for engaging the other end of the work, fluid-operated means for moving said center endwise, including a plunger supporting said center, a cylinder in which said plunger is located, valve mechanism for controlling the admission of fluid to said cylinder, mechanism for effecting a relative feed of said carrier and grinding wheel, and automatic mechanism controlled by said feed mechanism for operating said valve mechanism. 110
61. A grinding machine comprising a bed, a grinding wheel thereon, a pivoted work carrier, and work-supporting mechanism thereon including alined work centers, of which one is movable toward and from the other to engage the work, and mechanism supported in part on the bed and in part on said carrier for automatically moving said movable center. 115
62. A grinding machine comprising a bed, a grinding wheel thereon, a pivoted work carrier having supporting arms, a spindle mounted in one of said arms, a rotatable face plate or driving head supported on said spindle, a shaft journaled in said arm, gears connecting said face plate or driving head with said shaft, and means supported by the bed for driving said shaft. 120
63. A grinding machine comprising a bed, a grinding wheel thereon, a work carrier, mechanism for automatically feeding the work carrier toward and retracting it from the grinding wheel and bringing it to a state of rest on the completion of the retracting movement, work-rotating devices on said carrier, and mechanism by which the starting and stopping of said work-rotating devices is automatically controlled by the said feeding and retracting mechanism. 125
64. A grinding machine comprising a bed, a grinding wheel, a work support, a pivoted carrier by which a relative movement of said grinding wheel and work support may be effected, a longitudinally movable bar on which said carrier is pivoted, and a lever supported by the bed for reciprocating said bar. 130
65. A grinding machine comprising a bed, a grinding wheel, a work support, a pivoted

- carrier by which a relative movement of said grinding wheel and work support may be effected, a longitudinally movable bar on which said carrier is pivoted, a lever supported by the bed for reciprocating said bar, and power-actuated mechanism for rocking said lever.
66. A grinding machine comprising a bed, a grinding wheel, a work support, a pivoted carrier by which a relative movement of said grinding wheel and work support may be effected, a longitudinally movable bar on which said carrier is pivoted, a lever supported by the bed for reciprocating said bar, power-actuated mechanism for rocking said lever, and devices for tacking said lever in a predetermined position.
67. A grinding machine comprising a bed, a grinding wheel, a work support, a pivoted carrier by which a relative movement of said grinding wheel and work support may be effected, a longitudinally movable bar on which said carrier is pivoted, a lever supported by the bed for reciprocating said bar, clutch-controlled power-transmitting mechanism for rocking said lever, and manually-operated means for controlling the operation of said clutch.
68. A grinding machine comprising a bed, a grinding wheel, a work support, a pivoted carrier by which a relative movement of said grinding wheel and work support may be effected, a longitudinally movable bar on which said carrier is pivoted, a lever supported by the bed for reciprocating said bar, clutch-controlled power-transmitting mechanism for rocking said lever, a lock for said lever, and manually-operated means for controlling the clutch and said lock.
69. A grinding machine comprising a bed, a grinding wheel, a work support, a pivoted carrier by which a relative movement of said grinding wheel and work support may be effected, a longitudinally movable bar on which said carrier is pivoted, manually-operated means for reciprocating said bar, and automatic mechanism for reciprocating said bar.
70. A grinding machine comprising a bed, a grinding wheel, a work support, a pivoted carrier by which a relative movement of said grinding wheel and work support may be effected, a longitudinally movable bar on which said carrier is pivoted, a lever pivoted on said bed and engaged by one arm of said lever, a block on said bar, a gear journaled on said block and engaged with teeth on said bar, means on the bed for locking the lever against movement, means by which said lever may be held against movement, and means by which said gear may be rotated.
71. A grinding machine comprising a bed, a grinding wheel, a work support, a pivoted carrier by which a relative movement of said grinding wheel and work support may be effected, a longitudinally movable bar on which said carrier is pivoted, a lever supported by the bed for reciprocating said bar, clutch-controlled power-driven mechanism for rocking lever, and means throwing out the clutch and stopping and locking said lever in a predetermined position.
72. In a grinding machine, a bed, a work support, a grinding wheel, a shaft therefor, bearings in which said shaft is journaled, a driving shaft approximately alined with said grinding wheel shaft, means on said driving shaft for transmitting power thereto, means for coupling said shafts, and separate bearings for said driving shaft, whereby the grinding wheel shaft is relieved from the lateral thrust of the power-transmitting means on the driving shaft.
73. In a grinding machine, a bed, a work support, a grinding wheel, a shaft therefor, bearings in which said shaft is journaled, a driving shaft approximately alined with said grinding wheel shaft, means on said driving shaft for transmitting power thereto, separate bearings for the driving shaft, and a balanced drive coupling connecting the ends of said shafts.
74. A grinding machine, a bed, a work support, a grinding wheel, a shaft therefor, bearings in which said shaft is journaled, a driving shaft approximately alined with said grinding wheel shaft, means on said driving shaft for transmitting power thereto, separate bearings for said driving shaft, a coupling flexibly connecting the ends of said shafts, and a carriage supporting all of said bearings.
75. A grinding machine comprising a bed, a work support, a grinding wheel, a shaft therefor, a driving shaft approximately alined with the grinding wheel shaft, a coupling connecting the ends of said shaft, bearings for the grinding wheel shaft, bearings for the driving shaft, and a belt pulley on the driving shaft enclosing the driving shaft bearings.
76. A grinding machine comprising a bed, a work support, a grinding wheel, a shaft therefor, a driving shaft approximately alined with the grinding wheel shaft, a coupling connecting the ends of said shaft, a carriage having bearings for the grinding wheel shaft, a bracket affixed to said carriage and having bearings for the driving shaft, and a pulley on the driving shaft for transmitting power thereto.
77. A grinding machine comprising a work support for holding an elongated piece of work, a grinding wheel shaft, a grinding wheel thereon approximating in axial length the length of the work surface to be ground, said grinding wheel consisting of a plurality of sections or disks, and annular members at the ends of and between said sections for clamping said sections or disks together.

78. In a grinding machine, a bed, a work support, a grinding wheel, a conduit for delivering a liquid to the grinding wheel, a valve, automatic mechanism for effecting a relative feed of the work support and the grinding wheel, and mechanism for automatically operating said valve under control of said automatic feed mechanism to control the supply of liquid through said conduit.
79. In a grinding machine, a bed, a grinding wheel, means for delivering liquid to the grinding wheel, mechanism for rotating the work, and means for automatically cutting off the supply of liquid when the work rotating mechanism ceases to operate without affecting the continued rotation of the grinding wheel.
80. In a grinding machine, a bed, a grinding wheel, means for delivering liquid to the grinding wheel, a work holder having means for rotating the work, automatic feed mechanism for effecting a relative feed and retraction of the work holder and the grinding wheel in lines transverse to the axis of the grinding wheel, mechanism controlled automatically by said feed mechanism for admitting and cutting off the supply of liquid to said delivering means, and means controlled by said feed mechanism for starting and stopping said work rotating means.
81. In a grinding machine, a grinding wheel, means for rotating said wheel, work-rotating mechanism, means for delivering liquid to the grinding wheel, and mechanism independent of said wheel-rotating means for automatically controlling said transmitting devices and the supply of liquid to said delivery means, whereby liquid is initially delivered to said wheel when the work begins to rotate and is cut off when the work ceases to rotate.
82. In a grinding machine, a grinding wheel, means for rotating the grinding wheel, a work support, automatic feed mechanism for effecting a relative feed and retraction of the work and the grinding wheel, means for supplying liquid to the grinding wheel, work-rotating mechanism, and means independent of the grinding wheel rotating means whereby the supply of liquid and the operation of the work-rotating mechanism are automatically controlled by said feed mechanism.
83. In a grinding machine, a grinding wheel, a work support, mechanism for effecting a relative feed and retraction of said work support and grinding wheel in lines transverse to the axis of said wheel, a pump and a conduit for supplying liquid to the grinding wheel, a valve in said conduit, and automatic mechanism controlled by said feed mechanism for operating said valve.
84. In a grinding machine, a grinding
- wheel, a work support having means for rotating the work, mechanism for effecting a relative feed and retraction of said work support and grinding wheel in lines transverse to the axis of said wheel, a pump and a conduit for supplying liquid to the grinding wheel, a valve in said conduit, manually-operated means for actuating said valve, and mechanism controlled by said feed mechanism for automatically actuating said valve and stopping and starting the work-rotating means.
85. In a grinding machine, a bed, a grinding wheel, a work support, a carrier for effecting a relative transverse feed and retraction of said wheel and work support, a nut and a screw bearing against the bed and the carrier, one of said last-mentioned elements being rotatable and the other held against rotation, and automatic mechanism for rotating said rotatable element first in one direction through a predetermined arc and then reversing the rotation of said element.
86. A grinding machine comprising a bed, a grinding wheel, a work support having means for rotating the work, feed mechanism for effecting a relative movement of said grinding wheel and work support in lines transverse to the axis of said wheel, and fluid-operated mechanism controlling the operation of said feed mechanism and of the stopping and starting of the work-rotating means.
87. A grinding machine comprising a bed, a grinding wheel, a work support, work-rotating mechanism, and fluid-operated mechanism controlling the operation of said work-rotating mechanism.
88. A grinding machine comprising a bed, a grinding wheel, a work support having means for engaging and releasing the work, and fluid-operated mechanism for operating the last-mentioned means.
89. A grinding machine comprising a bed, a grinding wheel, a work support having means for engaging and releasing the work, feed mechanism, work-rotating mechanism, and fluid-operated mechanism for automatically controlling the operation of said work-engaging and releasing means, said feed mechanism and said work-rotating mechanism.
90. A grinding machine comprising a grinding wheel, a bed by which said wheel is supported, said bed being hollow to form a liquid reservoir with a catch basin thereabove to receive liquid from the grinding wheel, a pump and a conduit for supplying liquid from said reservoir to said grinding wheel, and a removable portable settling tank arranged to receive liquid from said catch basin and to deliver its overflow to said reservoir, said catch basin and reservoir being so arranged that, when said tank is

removed, the liquid is delivered from said nism and said work-rotating mechanism inactive when said carrier has been withdrawn to a predetermined extent.

91. A grinding machine comprising a grinding wheel, a work holder, work rotating mechanism, a carrier for effecting a relative movement of said work holder and grinding wheel transversely of the axis of said wheel, feed mechanism for feeding and withdrawing said carrier independently of

10 the work-rotating mechanism, and automatic mechanism for rendering said work-rotating mechanism inactive when said carrier has been withdrawn to a predetermined extent.

92. A grinding machine comprising a 15 grinding wheel, a work holder, work rotating mechanism, a carrier for effecting a relative movement of said work holder and grinding wheel transversely of the axis of said wheel, feed mechanism for feeding and

20 withdrawing said carrier, and automatic mechanism for rendering said feed mecha-

25 93. A grinding machine comprising a bed, a work holder including a tail center, fluid-operated means for moving said center endwise into engagement with the work, and means for regulating the pressure of said center against the work.

30 94. A grinding machine comprising a bed, a work holder including a tail center, fluid-operated means for moving said center endwise into engagement with the work, valve mechanism for controlling the operation of said fluid-operated means, and means for regulating the pressure of said center against the work.

In testimony whereof I have affixed my signature.

WILLIAM LE ROY BRYANT.
